ELECTRIC FLOOR LAMP

James H. Boye, Chicago, Ill.

Application December 19, 1932, Serial No. 647,869

6 Claims. (Cl. 240—81)

This invention relates to the art of electric floor lamps, and has reference more particularly to an improved cluster head for such lamps.

One well known and extensively used type of floor lamp employs a hollow cluster head made up of a lower bowl or base section mounted on the upper end of the tubular stem of the lamp, an intermediate or body section in the form of a short cylinder or ring carrying the radially branching hollow arms of the lights and the switch, and an upper cap or cover section; the three sections of the head being clamped together by a lower nut or an annular shoulder on the lamp stem and a collar fast on the central mast that supports the lamp shade. Within the hollow head is a vertical yoke or hickey formed with short upper and lower horizontal arms, the lower arm being apertured and tapped to engage with the upper threaded end of the lamp stem, and the upper arm being similarly apertured and tapped to receive and support the lower threaded end of the shade mast. The main conductor cord extends upwardly through the lamp stem and the lower arm of the hickey, whence the branch cords pass therefrom through the switch to the several arms of the lights.

This construction is faulty in several respects. The central section of the head carrying the light arms and the switch has a mere friction fit between the base and cap sections, so that, after the lamp is assembled, anyone, by taking hold of one of the light arms to turn the head in order to correct a looseness of the head on the lamp stem which often appears after the lamp has been delivered to a customer, will easily twist the branch wires around the hickey, cutting the insulation of the wires, and causing short circuits or breaking the switch, since the frictional grip of the arm-carrying section of the head on the top and base sections and of the lower end of the hickey on the base section is not sufficient to prevent relative rotation of the arm-carrying section and the base section and hickey, with the disastrous results above mentioned.

One object of the present invention is to provide a cluster head that will obviate the above-mentioned faults, and this I accomplish through a novel construction whereby all the parts of and within the head are securely locked against any relative rotation, whereby the wiring cannot be disturbed after it is once installed.

Again, in the known construction of cluster head above described the head and stem must be assembled at the factory, since if the stem be unscrewed from the head, the parts of the latter

will fall apart. This, together with the base which is also usually attached to the lower end of the stem at the factory, creates a large and bulky package, and makes impossible a customer's choice between different styles of heads and stems 36 when purchasing.

Another object of the present invention is to provide a floor lamp of such a character and construction that at least the head and stem can be separately assembled in separate units and 65 packed and shipped in unit boxes. As the base is usually screwed onto the lower end of the stem, this may also be packed and shipped in unit boxes if desired. This not only greatly reduces the size, bulk and weight of packages, but a customer may, 70 if he so desires, make a selection between different ornamental styles of head and stem, and also select any style of base desired.

As will be seen from the following detailed description, the construction of my improved floor 75 lamp is such that the cluster head and stem, as well as the base if desired, can be assembled by merely passing the main cord through the stem and base and then screwing the parts together, and this construction effectuates a still further 80 object of the invention, which is to provide a floor lamp construction such that its several unit parts can easily be assembled by the customer after the lamp has been delivered without requiring previous assembling at the factory or the services 85 of a mechanic or electrician to set the lamp up for use.

In the accompanying drawings I have illustrated two slightly differing physical embodiments of the invention, and referring thereto:— 90

Fig. 1 is an elevation of the complete cluster head shown as mounted on the upper end of a lamp stem.

Fig. 2 is a horizontal section through the head on the line 2—2 of Fig. 1. 95

Fig. 3 is a vertical axial section through the head and through the lower and upper portions of the shade mast and lamp stem respectively.

Fig. 4 is an enlarged vertical axial section through the means for uniting the sections of the 100 head and attaching the shade mast.

Fig. 5 is an elevation, similar to Fig. 1, of a slightly modified form of the invention.

Fig. 6 is a vertical axial section, similar to Fig. 3, of the modified form shown in Fig. 5. 105

First describing the embodiment of the invention illustrated in Figs. 1 to 4 inclusive, 10 designates the usual tubular stem of the lamp, which ordinarily consists of a section of gas pipe, to the upper end of which is attached by means later 110

described a hollow sectional cluster head. In the form herein shown, this cluster head comprises a hollow generally bowl-shaped base section 11, preferably a casting, an annular intermediate or body section 12 that fits into the upper end of the base section 11 and projects somewhat thereabove, and a cap or cover section 13, the lower end of which rests upon and telescopes over the upper end of the body section 12 in the manner clearly shown in Fig. 3. The base section 11 may be plain or may be given an ornamental configuration as indicated in Fig. 1. On the lower end of the base section 11 is an externally threaded hollow boss 14.

15 Rigidly mounted at its lower end in the base section 11 (and preferably integral with the latter) is a central hickey taking the form of a vertical tube 15, which communicates at its lower end through the bottom of the base section 11 and hollow boss 14 with the tubular lamp stem 10 to permit the passage of the conductor cord C therethrough. The tube 15 is formed with a lateral hole 16 for the passage of the conductor cord into the hollow of the head, wherein the several branches c from the cord C lead through a switch S into and through a plurality of tubular branch arms 17 that carry the lights 18, the switch S being mounted as usual on the inner face of the intermediate head section 12. The upper end of 20 the hickey tube 15 is threaded to receive a pipe union 19, and overlying the latter is the centrally apertured cap or cover member 13. The three sections of the head are united as a self-contained unit by means of a hollow clamp screw 20 (Fig. 4) 25 that extends through the aperture of the cap 13 and screws into the upper end of the pipe union 19. By adjusting the pipe union 19 on the hickey tube 15 to just the required height, the parts of the head may be tightly and securely united. 30 The top of the clamp screw 20 has a threaded countersink 21 (Fig. 4) to receive the lower threaded end of the usual shade mast 22, the tube being rendered relatively non-rotatable when desired by a lock nut 23. By backing off the lock 35 nut 23, the shade mast 22 may be disconnected without disturbing the integrity of the head. If it is desired to disassemble the head, this may be done by turning down the lock nut 23 and then backing out the clamp screw 20 by rotating the mast 22. 40 The upper peripheral portion of the base section 11 of the head is formed with a group of radially projecting seats 24, best shown in Fig. 2, these seats embracing the sides of the light-carrying arms 17. This construction securely 45 locks the arms 17 against any rotational movement relatively to the base section 11 of the head, and since the hickey tube 15 is rigid with the base section, any rotational movement imparted to any of the arms 17 does not and cannot disturb 50 the original setup of the wiring within the hollow head, and consequently preserves the wiring against abrasion, tension or other injury and possible short-circuiting and strain on the switch. 55 The lamp stem 10 has a threaded upper end, and is separably connected to the head by a pipe union 25, which permits ready separation of the head and stem without disturbing the integrity of the head and the parts therein. The pipe union 25 also, in the construction shown, serves the function of an upper clamping nut for the 60 usual ornamental covering of the stem 10 which, in practice, consists of a group of superposed sleeves 26, the lowermost of which is stepped on 65 a lower clamp nut (not shown) on the lower

threaded end of the stem which screws into the base.

The modification illustrated in Figs. 5 and 6 is identical with that hereinabove described except that, in lieu of the seats 24 on the top edge of the base section 11, I cast integral with the base section 11 a group of hollow arms 27 in which the arms 17 are sheathed. These covering arms 27 may, as shown in Fig. 5, continue the ornamental character and effect of the base section 11 up to the base of the lights 18. Of course they have the same mechanical effect of supporting the arms and locking them against rotation relatively to the base section as do the seats 24 of the construction first described. In both of the constructions shown, the arms 17 may be rigidly secured to the intermediate head section 12 by passing the inner ends of the hollow arms through holes in the member 12 and then swaging them over on the inner side, as shown at 17'. This arm sheathing structure is readily made by first assembling the arms 17 with the head section 12, then placing these parts in a suitable mold, and pouring in the metal forming the complete casting 11, 27.

As above stated, the described construction permits the head and the stem, and the base also if desired, to be separately packaged in unit packages, and the user will have no trouble in assembling the lamp, since all that is required is to pass the main cord down through the stem and through the base, then screw the head, stem and base together, and attach the socket plug and the lamp is then ready for use. There are no parts or fittings that can become loosened or displaced from operative position when the head and stem are separated, and if, when they are assembled, any looseness develops in the pipe union connection, manifestly the head can be screwed down further into the latter without 105 in the least disturbing or injuring the wiring within the head.

I believe that the broad principle of a sectional cluster head structure carrying branching light-carrying arms so constructed that the 110 partial rotation of the head to screw the same tight into the stem cannot disturb the wiring within the head, is new with me, and hence I do not limit the invention to the particular mechanical embodiments of the principle herein disclosed for purposes of illustration, but reserve all 115 such variations and modifications as fall within the spirit of the appended claims.

I claim:

1. In an electric floor lamp cluster head, the 120 combination of a bowl-shaped base section adapted to be mounted on a lamp stem and formed in its upper edge with a plurality of radially projecting seats, an intermediate annular body section fitting into the upper end of 125 said base section, a plurality of tubular light-carrying arms rigidly secured to said intermediate section and occupying said seats, a cover section overlying said intermediate section, and means for uniting said sections as a self-contained 130 unit.

2. In an electric floor lamp cluster head, the combination of a bowl-shaped base section adapted to be mounted on a lamp stem, a plurality of hollow arms integral with and branching from the upper portion of said base section, an intermediate annular body section fitting into the upper end of said base section, a plurality of tubular light-carrying arms secured to said intermediate section and extending through said 145 150

- hollow arms, a cover section overlying said intermediate section, and means for uniting said sections as a self-contained unit.
3. In an electric floor lamp cluster head, the combination of a bowl-shaped base casting adapted to be mounted on a lamp stem, an annular body member fitting into and extending above the upper end of said base casting, radially extending light-carrying arms rigidly and permanently attached at their inner ends to said body member, means on said base casting engaged with said arms to prevent relative rotation of said base casting and body member, a cover closing the upper end of said body member, and means for clamping together said base casting, body member, and cover.
4. In an electric floor lamp cluster head, the combination of a bowl-shaped base casting adapted to be mounted on a lamp stem, an annular body member fitting into and extending above the upper end of said base casting, radially extending light-carrying arms rigidly and permanently attached at their inner ends to said body member, means on said base casting engaged with said arms to prevent relative rotation of said base casting and body member, a central vertical hickey tube integral with the bottom of said base casting and extending upwardly through said body member, said tube having its bore extending through the bottom of said base casting and formed with a lateral hole for the passage of a conductor cord, a cover closing the upper end of said body member, and means attached to the upper end of said tube for clamping said cover on said body member.
5. In an electric floor lamp cluster head, the combination of a bowl-shaped base casting adapted to be mounted on a lamp stem, an annular body member fitting into and extending above the upper end of said base casting, radially extending light-carrying arms rigidly and permanently attached at their inner ends to said body member, means on said base casting engaged with said arms to prevent relative rotation of said base casting and body member, a central vertical hickey tube integral with the bottom of said base casting and extending upwardly through said body member, said tube having its bore extending through the bottom of said base casting and formed with a lateral hole for the passage of a conductor cord, a cover closing the upper end of said body member, and means attached to the upper end of said tube for clamping said cover on said body member.
6. In an electric floor lamp cluster head, the combination of a bowl-shaped base section adapted to be mounted on a lamp stem and formed with a plurality of integral radially extending arm supports, an intermediate annular body section fitting into the upper end of said base section, a plurality of tubular light-carrying arms at their inner ends secured to said intermediate section and engaged with said supports, a cover section overlying said intermediate section, and means for uniting said sections as a self-contained unit.
